UNITED STATES PATENT OFFICE.

ERNEST SOLVAY, OF BRUSSELS, BELGIUM, ASSIGNOR TO THE SOLVAY PROCESS CO., OF SYRACUSE, NEW YORK.

APPARATUS FOR DRYING BICARBONATE OF SODA.

SPECIFICATION forming part of Letters Patent No. 683,187, dated September 24, 1901.

Application filed April 17, 1896. Serial No. 587,994. (No model.)

To all whom it may concern:

Be it known that I, ERNEST SOLVAY, of Brussels, Belgium, have invented new and useful Improvements in Drying Apparatus, 5 of which the following, taken in connection with the accompanying drawings, is a full, clear, and exact description.

My invention relates to improvements in drying apparatus of the class set forth in my prior patent, No. 617,367, issued January 10, 1899, particularly applicable for use in the manufacture of bicarbonate of soda, and has for its object the production of a device of such construction that its drying or filtering surface is automatically and continuously cleaned; and to this end it consists, essentially, in the combination, construction, and arrangement of the component parts of a drying apparatus, as hereinafter fully described, 20 and pointed out in the claims.

In describing this invention reference is had to the accompanying drawings, forming part of this specification, in which like letters indicate corresponding parts in both views.

25 Figure 1 is a longitudinal vertical section of my improved drying apparatus; and Fig. 2 is a transverse section taken on line 2-2, Fig. 1.

The drying apparatus set forth in the afore-30 said patent is of such construction that the operation of the filtering - body must be stopped from time to time in order to effect cleaning of its drying or filtering surface. My present invention is designed to obviate 35 stoppage of the filtering-body for said purpose and is of such construction that cleaning of its drying or filtering surface is automatically and continuously effected during the operation thereof, and consequently its 40 practicability and capacity are greatly enhanced.

A is a receptacle, of any desirable form, size, and construction, and α is a pipe or conduit for discharging thereinto the material 45 to be dried, which may be held in suspension by a suitable liquid or may be merely moistened thereby. If desired, this pipe may be omitted and the material to be dried may be otherwise discharged within the receptacle A.

50 B is a filtering-body, of any desirable form, size, and construction, having a portion of its

surface movable into and out of the fluent or moist material in the receptacle A. The body B preferably consists of a revoluble cylinder partially surrounded by air or other 55 drying fluid and formed with a perforated peripheral drying or filtering surface b , a perforated ring b' , surrounding the surface b and formed of any suitable material, a main chamber B' , and branch chambers B^2 , extending from one side of the surface b to the chamber B' and provided with openings b^2 , communicating with said chamber B' . The body B is actuated by any suitable driving means, as a gear b^3 , and is formed with closed end 60 walls having projecting trunnions $b^4 b^4$, which are journaled in bearings $a' a'$ and are usually formed hollow.

C represents any suitable means for sub-70 jecting one side of the drying or filtering surface b and the chambers B^2 to a pressure different from that on the opposite side of said surface, and D suitable means for automatically subjecting said side of the drying or filtering surface and the chambers B^2 to a 75 pressure different from the former pressure. These means C D may be of any desirable form, size, and construction, but are preferably so constructed as to first subject the chambers B^2 and the adjacent side of the 80 drying or filtering surface b to a lower pressure than that on the opposite or outer side of said surface b and to afterward subject said chambers and adjacent side of the surface b to a pressure higher than that on the 85 opposite or outer side of the surface b . The means C D preferably consist of stationary conduits or passages extending through the trunnions $b^4 b^4$ and having the adjacent ends of their inclosing walls suitably connected 90 together. As clearly seen in Fig. 1, the conduit or passage C communicates with the chamber B' of the body B and the conduit or passage D is provided with a yielding wall D' , formed of rubber or other suitable material, 95 and a branch conduit d , which projects laterally from said wall, so as to be free to yield lengthwise, and successively communicates with the openings b^2 of the chambers B^2 as the body B is revolved. I usually arrange the 100 means C so that the chambers B^2 are first subjected to the lower pressure after the opera-

tion of the means D, when their drying or filtering surfaces are within the fluent or moist material to be dried and are continuously subjected to said pressure after their elevation above the main body of said material and until the dried material is removed from the drying or filtering surface b by a knife E or any other suitable device. The means D is so arranged as to subject the chambers B² 5 to the higher pressure after the dried material is removed from their surfaces b in order to discharge substantially all material from the outer ends of the perforations of said surfaces.

15 As in my aforesaid patent the lower pressure within the body B forces the liquor or moisture in the material to be dried through the drying or filtering surface of said body, causes the material to accumulate and remain 20 on said drying or filtering surface, and thoroughly dries said accumulated material when elevated above the main body of the fluent or moist material by compelling the moisture between its particles to enter the filtering- 25 body and by drawing through said material the air or other drying fluid surrounding the unsubmerged portion of said filtering-body. In the operation of my drying apparatus the lower pressure within the body B is preferably sufficient to cause a given amount by 30 weight of the moisture or liquid in the moist or fluent material and the air or other drying fluid partially surrounding the filtering-body B to feed through the conduit C at a greater 35 speed than a similar amount of said moisture or liquid and air or other drying fluid feeds through the filtering-surface of said body from the outer side thereof.

The construction and operation of my improved drying apparatus will be readily perceived upon reference to the foregoing description and the accompanying drawings, and it will be particularly noted that I do not herein limit myself to the exact construction and arrangement of any of the component parts thereof, as the same may be materially varied without departing from the spirit of my invention.

Having thus fully described my invention, 45 what I claim as new, and desire to secure by Letters Patent, is—

1. A drying apparatus comprising a receptacle for receiving the moist or fluent material to be dried, a filtering-body partially surrounded by air or other drying fluid and having a portion of its surface movable into engagement with said material, said filtering-body being provided with a series of chambers projecting from its inner surface, a conduit or passage for withdrawing a given amount by weight of the moisture or liquid in the moist or fluent material and the air or other drying fluid from the inner side of the filtering-surface at a greater speed than a 55 similar amount of said moisture or liquid and air or other drying fluid feeds through the filtering-surface from the outer side thereof,

and a second conduit or passage unconnected with the former conduit or passage for subjecting said chambers successively to an increased 70 pressure after the removal of the filtered material from the corresponding portions of the outer side of the filtering-surface and during the passage of the moisture or liquid and the air or other drying fluid through an adjacent 75 portion of said surface, into the corresponding chamber, substantially as and for the purpose specified.

2. A drying apparatus comprising a receptacle for receiving the moist or fluent material to be dried, a filtering-body partially surrounded by air or other drying fluid and having a portion of its surface movable into engagement with said material, a conduit or passage connected to the interior of the filtering- 80 body and adapted to be connected with means for maintaining a partial vacuum within the filtering-body and retaining the material in position on the exterior face of said body, and a second conduit or passage connected to the 85 interior of the filtering-body for raising the pressure within a portion of the filtering-body after the removal of the filtered material from the corresponding portion of the filtering-surface and during the maintenance of the partial 90 vacuum within an adjacent portion of said body by the first conduit or passage, substantially as and for the purpose described.

3. A drying apparatus comprising a receptacle for receiving the material to be dried, 100 and a filtering-body, having a portion of its surface movable into engagement with said material, and provided with a series of chambers extending from one side of said surface, and formed with openings thereinto, and a 105 conduit or passage provided with a yielding branch for successively communicating with said openings and subjecting the chambers to a pressure different from that previously 110 therein, substantially as and for the purpose specified.

4. A drying apparatus comprising a receptacle for receiving the material to be dried, and a filtering-body having a portion of its surface movable into engagement with said material, and provided with a main chamber, a series of branch chambers extending from one side of said surface and communicating with the main chamber, means for removing the filtered material from said opposite side, 115 and a conduit or passage communicating with the main chamber, said conduit or passage operating to subject the branch chambers after the removal of the filtered material to a pressure different from that on the opposite 120 side of said surface after removal of the filtered material, substantially as and for the purpose set forth.

5. A drying apparatus comprising a receptacle for receiving the material to be dried, a 130 filtering-body, having a portion of its surface movable into engagement with said material, and provided with a main chamber, a series of branch chambers extending from one side

of said surface and communicating with the former chamber, a conduit or passage communicating with the main chamber for subjecting the branch chambers to a pressure different from that on the opposite side of said surface, and a second conduit or passage for subjecting said branch chambers to a pressure different from the former pressure, substantially as and for the purpose specified.

10 6. A drying apparatus comprising a receptacle for receiving the material to be dried, and a filtering-body, having a portion of its surface movable into engagement with said material, and provided with a main chamber, a series of branch chambers extending from one side of said surface and having openings communicating with the former chamber, a conduit or passage communicating with the main chamber for subjecting the branch 15 chambers to a pressure different from that on the opposite side of said surface, and a second conduit or passage having a yielding branch for communicating with said openings and subjecting the chambers to a pressure different 20 from the former pressure therein, substantially as and for the purpose set forth.

7. A drying apparatus comprising a receptacle for receiving the material to be dried, and a filtering-body, having a portion of its 30 surface movable into engagement with said material, and provided with a main chamber, a series of branch chambers extending from one side of said surface and having openings communicating with the former chamber, a 35 conduit or passage communicating with the main chamber for subjecting the branch chambers to a pressure different from that on the opposite side of said surface, a second conduit or passage provided with a yielding 40 wall, and a branch projecting from the wall for successively communicating with said openings and subjecting the chambers to a pressure different from the former pressure 45 therein, substantially as and for the purpose specified.

8. A drying apparatus comprising a receptacle for receiving the material to be dried, a revolvable filtering-body, having a portion of its surface movable into engagement with 50 said material, and provided with a main chamber, and a series of branch chambers extending from one side of said surface and having openings communicating with the former chamber, a stationary conduit communicating 55 with the main chamber for subjecting the branch chambers to a pressure different from

that on the opposite side of said surface, and a second stationary conduit for communicating with said openings and subjecting the chambers to a pressure different from the former pressure therein, substantially as and for the purpose described.

9. A drying apparatus comprising a receptacle for receiving the material to be dried, a revolvable filtering-body, having a portion 60 of its surface movable into engagement with said material, and provided with a main chamber, and a series of branch chambers extending from one side of said surface and having openings communicating with the former 65 chamber, a stationary conduit communicating with the main chamber for subjecting the branch chambers to a pressure different from that on the opposite side of said surface, and a second stationary conduit connected to the 70 former conduit and formed with a laterally-projecting branch for successively communicating with said openings and subjecting the chambers to a pressure different from the former pressure therein, substantially as and for 75 the purpose set forth.

10. A drying apparatus comprising a receptacle for receiving the material to be dried, a revolvable filtering-body, formed with opposite hollow trunnions and having a portion 80 of its surface movable into engagement with said material, said body being provided with a main chamber, and a series of branch chambers extending from one side of said surface and having openings communicating with 85 the former chamber, a stationary conduit projecting through one hollow trunion and communicating with the main chamber for subjecting the branch chambers to a pressure different from that on the opposite side of 90 said surface, and a second stationary conduit projecting through the other hollow trunion and communicating with said openings connected to the former conduit and formed with a laterally-projecting branch for successively 95 communicating with said openings and subjecting the chambers to a pressure different from the former pressure therein, substantially as and for the purpose specified.

In testimony whereof I have hereunto 100 signed my name, in the presence of two attesting witnesses, at Brussels, Belgium, this 26th day of February, 1896.

ERNEST SOLVAY.
